UNITED STATES PATENT OFFICE.

GEORGE W. ALLEN, OF HYDE PARK, MASSACHUSETTS, ASSIGNOR TO B. F. STURTEVANT COMPANY, OF HYDE PARK, MASSACHUSETTS, A CORPORATION OF MASSACHUSETTS.

FAN OR BLOWER.

Application filed May 28, 1919. Serial No. 300,271.

To all whom it may concern:

Be it known that I, GEORGE W. ALLEN, a citizen of the United States, residing at Hyde Park, Boston, in the county of Suffolk and State of Massachusetts, have invented certain new and useful Improvements in Fans or Blowers; and I do hereby declare the following to be a full, clear, and exact description of the invention, such 10 as will enable others skilled in the art to which it appertains to make and use the same.

The present invention relates to fans or blowers and more particularly to apparatus of this character adapted for exhausting air, gas or the like.

It is well known to those skilled in the art that fans of this type comprise generally a casing of suitable form with a fan 20 rotatably mounted therein, the casing being generally provided with one or more lateral intake openings and a peripheral discharge opening. It is frequently necessary and desirable to vary the angle of the peripheral 25 discharge opening either for convenience in making connection with an existing installation or for other purposes, and accordingly one object of the invention contemplates the provision of a casing which is 30 adjustable relative to its supporting members in order to vary the position of the peripheral discharge opening as desired.

With this object in view one feature of the invention consists in the combination of 35 a fan casing having a series of suitably disposed holes located in opposite walls, together with two co-operating supports between which the casing is secured by bolts or other securing means passed through 40 openings formed in the supports and aligned with openings in the casing.

It is highly desirable in apparatus of this sort that the fan shaft and fan supported thereon shall be mounted independently of 45 the casing so that the vibrations of the fan and shaft shall not be transmitted directly to the casing. With this end in view another object of the invention contemplates the provision of oppositely disposed pedestals or supports provided with shaft bearings for the ends of the fan shaft and with suitably located openings adapted to align 50 with openings formed in opposite sides of the fan casing to receive bolts or other mem-

bers for securing the casing to the supports 55 independently of the shaft.

In the simplest and most efficient form of the invention which has yet been devised the bolt receiving openings upon opposite faces of the fan casing are arranged concentrically with the axis of the fan shaft so that the angular adjustment of the casing relative to the supports does not disturb the proper relation of the fan casing with respect to the rotating fan. 65

Still further features of the invention consist in certain novel features of construction, combinations and arrangements of parts hereinafter described and claimed, the advantages of which will be obvious to those 70 skilled in the art from the following description.

In the accompanying drawings illustrating the invention, Figure 1 is a view in front elevation of a preferred form of my invention; Fig. 2 is a view in side elevation of the same; Fig. 3 is a view in front elevation of a modification; Fig. 4 is a view in side elevation of the same with a portion broken away; and Fig. 5 is a sectional view 80 of a preferred form of lubricating mechanism. 75

According to the preferred embodiment of the invention, the fan casing is provided with a number of lateral, circularly arranged securing means, which may be a number of openings adapted to receive bolts or other securing means, whereby the casing may be adjustably secured to the supports. In order that the rotative adjustment of the 90 fan casing shall not disturb the proper relation between the moving fan and the casing the securing means are accurately located in concentric relation with respect to the axis of rotation of the fan shaft which in the 95 illustrated embodiment of the invention is journaled in bearings upon the casing supports independently of the fan casing.

A fan of the usual type (not shown), having a shaft 2, is mounted within a casing 100 4 having axial screened intake openings 6 and 8 and a peripheral exhaust opening 10. A pair of rings 12 are integrally formed and faced upon the opposite sides of the casing, along which are provided a series of openings 14 for receiving screws, bolts or the like. In addition a number of circularly arranged openings 16 are provided in 105

the sides of the casing 4, preferably concentric with, and along the same radius lines as the openings 14. The shaft 2 projects beyond the inlet openings 6 and 8, and is 5 journalized within bearings 18 and 20 carried by pedestal supports 22 and 24. The supports 22 and 24 are provided with a pair of openings 26 and a second pair of openings 28, the former of which are adapted 10 to register with any two adjacent openings 14, and the latter of which with any two adjacent openings 16. The casing 4 may be secured in rotatably adjusted position with respect to the supports 22 and 24 by means 15 of bolts, screws or similar securing means 29 co-operating with the openings 28 and 16 and 26 and 14, respectively. In this manner, the casing 4 may be mounted with the peripheral opening 10 in any one of a 20 number of different angular positions relative to the supports 22 and 24.

It will be observed from an inspection of Figure 2 that the openings 26 and 28 formed in each one of the pedestal supports are 25 disposed upon radial lines corresponding to the lines upon which the respective openings 14 and 16 are located so that as the casing is adjusted rotatively the bolt receiving holes 26 and 28 will register with successive sets of bolt receiving holes 14 and 16. In addition to the rotative adjustment of the casing which may be secured with this construction, it has the further advantage that the position of the casing may be 30 reversed between the pedestals so that the blower will operate with either a right hand or a left hand discharge. This reversal of the casing is permitted by the fact that the opposite sides are furnished with bolt holes located in identically the same manner and 35 adapted to co-operate with either one of the two supporting pedestals.

In Figures 3 and 4 is illustrated a fan casing constructed in accordance with the 40 principles of this invention, but modified to provide for a closed intake. This type of construction may be employed for pumping gas from a retort. The walls of the intake are provided with stuffing boxes through 45 which the fan shaft projects. The stuffing boxes do not support the shaft which is journaled in the bearings 18 and 20, as in the form of the invention illustrated in Figs. 1 and 2. In order to permit the use 50 of the same supports 22 and 24 with this construction additional supporting members are provided between the casing and the ordinary standard supports and pedestals. The intake duct connecting the inlet openings 6 and 8 is indicated at 30 and is provided with a main inlet opening 32, which 55 may be connected to the usual conduit. The walls of the duct 30 are provided with stuffing boxes 34, through which the shaft 2 projects. One of the stuffing boxes is

shown in detail in Figure 5. It comprises a body portion 36 adapted for attachment to the intake housing, a ring 38 secured therein and having a packing-receiving opening 40, packing 42 therein, a grease cup 44, and a gland 46 for securing the packing 42 in place in the packing-receiving opening 40. It will be noted from an inspection of Figure 5 that the packing comprises a series of flexible packing discs 47 disposed upon opposite sides of a peripherally grooved disc 48 which is located at the bottom of the grease duct 49 and is adapted to receive and distribute lubricant about the rotating shaft 2. The packing rings 47 in this construction serve to prevent the escape of gas or air from the interior of the intake duct outwardly along the shaft. By means of this arrangement, the gas within the chamber 30 cannot escape along the shaft 2 to the outside air, and the grease cannot escape along the shaft 2, either into the outside air or into the chamber 30.

The supports 22 and 24, if of standard size, such as are suitable for use in connection with the structure of Figs. 1 and 2, must be mounted so far away from the casing 4 that it is not practicable to secure the casing 4 thereto in the same manner as that described in connection with the description of Figs. 1 and 2. In order that the standard supports 22 and 24 may be employed, additional supports 52 and 54 are interposed between the supports 22 and 24 and the casing 4, each of which supports 52 and 54 is provided with openings similar to the openings 26 and 28 shown in Figs. 1 and 2, by means of which the casing 4 may be secured to the supports 52 and 54. Openings corresponding to the openings 26 and 28 extend throughout the width of the supports, whereby the support 54 may be secured to the support 24, and the support 52 to the support 22 by the same bolts 29 which secure the casing 4 to the supports 52 and 54.

In this manner the casing 4 may be secured to the supports 52 and 54 independently of the fan, the shaft 2 of which, though passing through the stuffing boxes 34 in the 115 walls of the chamber 30, is nevertheless supported in the bearings 18 and 20 upon the supports 22 and 24. By means of this arrangement, all the advantages accruing to the structure illustrated in Figs. 1 and 2 120 may be obtained, with the additional advantage that the inlet openings 6 and 8 are not exposed to the outside air.

The nature and scope of the present invention having been indicated and the several machines embodying the several features of the invention in their preferred form having been specifically described, what is claimed is:

1. A fan comprising a fan casing having 130

axial intake openings and provided on each face with a concentric series of bolt holes located without the periphery of said openings, a pair of pedestals having bolt holes 5 below the intake openings and arranged to align with a portion of the bolt holes of the casing for supporting the casing wholly below the axial intake openings in different angular positions of the casing and without 10 interference with the intake openings.

2. A fan having, in combination, a shaft, a casing provided with a peripheral discharge opening and lateral inlet openings through which the shaft projects, an intake 15 duct leading to the inlet openings from a main inlet opening and having wall portions through which the shaft projects, a pair of supports below said wall portions to which the casing is secured and a pair of supports 20 adjacent to the first-named pair of supports having bearings for the shaft.

3. A fan having, in combination, shaft, a casing provided with a peripheral discharge opening and lateral inlet openings 25 through which the shaft projects, a pair of

bearings for the shaft, an intake duct leading to the inlet openings and having a main inlet opening, a pair of fluid-tight stuffing boxes mounted in the walls of the duct through which the shaft projects, a pair of supports below the stuffing boxes to which the casing may be rotatably adjustably secured, a pair of supports for the bearings, and means for rotatably adjustably securing the casing to the supports. 30 35

4. A fan comprising a rotor, a shaft, a fan casing having an axial intake opening and a tangential discharge opening, a pedestal adjacent the intake opening having at its top a bearing for the rotor shaft and intermediate its top and bottom a support for the fan casing located below the axial intake opening and without interfering therewith, and connections between the casing and the support comprising bolts adapted 40 to register with different bolt holes to vary the angular position of the casing and its discharge opening. 45

GEORGE W. ALLEN.
